UNITED STATES PATENT OFFICE

1,974,105

PIPE TONGS

Clarence Alex Eagan, Barnsdall, Okla.

Application April 13, 1934, Serial No. 720,487

4 Claims. (Cl. 81—91)

The present invention relates to pipe tongs and has for its object to provide in combination a pair of swingable grips or jaws and a pair of slidable grips or jaws cooperatively associated in 5 a compact and convenient manner for easy and efficient operation.

Another important object of the invention resides in the provision of pipe tongs of this nature which possess simplicity, durability, ease 10 of manipulation, cheapness of manufacture and being well adapted to the purpose for which the mechanism is designed.

With the above and numerous other objects in view as will appear as the description proceeds, 15 the invention consists in certain novel features of construction, and in the combination and arrangement of parts as will hereinafter be more fully described and claimed.

In the drawings:

20 Figure 1 is an elevation of this mechanism showing the slits or jaws in open position.

Figure 2 is a similar view partly in section showing the jaws or slits in closed position.

Figure 3 is an elevation at right angles to that 25 shown in Figures 1 and 2.

Figure 4 is an end elevation.

Referring to the drawings in detail it will be seen that numerals 5 denote a pair of plates disposed in coextensive parallelism by means of 30 bolts 6, 6, and 7. These plates are provided with semi-circular edges 8 integrally connected by a semi-circular web 9 having a pair of openings 10 situated between the bolt 7 and the bolts 6, 6. Grips or jaws 11 have shanks 12 slidable through 35 the openings 10 and are limited in movement by pin and slot connections 14. Numerals 15 denote a pair of grips or jaws on curved shanks 16 the ends of which are rockable on the bolts 6.

40 Curved links 17 and 18 are pivotally engaged with intermediate portions of the shanks 16 as at 19. The link 17 is substantially straight for about one-half of its length and then is slightly curved and pivotally engaged as at 20 with a lever 21 rockably mounted on the bolt 7. The link 18 is of an ogee curvature and is pivotally engaged as at 22 with the lever 21. The pivotal 45 connections 20 and 22 are on opposite sides of the bolt 7. The lever 21 when swung from the position shown in Figure 1 to the position shown in Figure 2 causes the grips or jaws 15 to move from open to closed position and simultaneously the links 17 and 18 engage the shanks 12 and move the grips or jaws 11 toward the jaws or 50 grips 15. All four of these grips or jaws, there-

fore, move toward each other or away from each other simultaneously.

It is thought that the construction, operation, utility and advantages of this invention will now be quite apparent to those skilled in this 60 art without a more detailed description thereof.

The present embodiment of the invention has been described in considerable detail merely for the purposes of exemplification since in actual practice it attains the features of advantage 65 enumerated as desirable in the statement of the invention and the above description.

It will be apparent that changes in the details of construction, and in the combination and arrangement of parts may be resorted to 70 without departing from the spirit or scope of the invention as hereinafter claimed or sacrificing any of its advantages.

Having thus described my invention, what I 75 claim as new is:

1. A device of the class described including a body, a lever pivotally mounted intermediate its ends and adjacent one end within the body, a pair of shanks pivotally mounted in the body and having jaws on the ends thereof, links engaged with intermediate portions of the shanks and with the lever one to each side of the pivot thereof, a pair of jaws having shanks slidable in the body and engageable by intermediate portions of the links to be actuated thereby. 80

2. A device of the class described including a body, a lever pivotally mounted intermediate its ends and adjacent one end within the body, a pair of shanks pivotally mounted in the body and having jaws on the ends thereof, links engaged with intermediate portions of the shanks and with the lever one to each side of the pivot thereof, a pair of jaws having shanks slidable in the body and engageable by intermediate portions of the links to be actuated thereby, the last 85 mentioned shanks having pin and slot connections with the body. 90

3. A device of the class described including a body, a lever pivotally mounted intermediate its ends and adjacent one end within the body, a pair of shanks pivotally mounted in the body and having jaws on the ends thereof, links engaged with intermediate portions of the shanks and with the lever one to each side of the pivot thereof, a pair of jaws having shanks slidable in the body and engageable by intermediate portions of the links to be actuated thereby, the last 95 mentioned shanks having pin and slot connections with the body, said body being in the form of a pair of spaced parallel coextensive 100

105

110

plates having arcuate edges connected by an arcuate web, in which is located the openings in which the last mentioned shanks are slid able.

4. A device of the class described including a body, a lever pivotally mounted intermediate its ends and adjacent one end within the body, a pair of shanks pivotally mounted in the body and having jaws on the ends thereof, links engaged with intermediate portions of the shanks and with the lever one to each side of the pivot thereof, a pair of jaws having shanks slid able in the body and engageable by intermediate por-

tions of the links to be actuated thereby, the last mentioned shanks having pin and slot connections with the body, said body being in the form of a pair of spaced parallel coextensive plates having arcuate edges connected by an arcuate web, in which is located the openings in which the last mentioned shanks are slid able, one of the links being substantially straight for half of its length and the other half being slightly curved, and the other link having an ogee curvature.
